MILLARD F. FIELD, OF WINTHROP, MASSACHUSETTS.

PICKER-STICK CHECK.

1,286,570.

Specification of Letters Patent. Patented Dec. 3, 1918.

Application filed February 4, 1918. Serial No. 215,229.

To all whom it may concern:

Be it known that I, MILLARD F. FIELD, a citizen of the United States, residing at Winthrop, in the county of Suffolk, State 5 of Massachusetts, have invented a certain new and useful Improvement in Picker-Stick Checks, of which the following is a specification, reference being had therein to the accompanying drawings.

10 My invention relates to picker-stick checks for looms and it has for its object to provide an improved check of that type which comprises two members supported at opposite sides of the picker-stick slot and yieldingly engaging opposite sides of the stick to stop the latter when it is driven outward by the shuttle.

My improved picker-stick check comprises two stick-engaging jaws independently or 20 separately supported on the lay of the loom at opposite sides of the path of travel of the picker-stick, with provision for either independent or conjoint swinging movement transversely thereof, but connected together 25 so as to yieldingly stand in the path of the stick by means that is carried by said jaws themselves. By this construction the side- 30 wise pressure of the two jaws on the stick, when the latter is driven between them, is equalized, while at the same time the acting 35 portions of the check are permitted to adjust themselves either forward or rearward so as to conform to the plane of movement to which the picker-stick is confined by reason of the engagement of the shuttle-tip within the cavity formed in the acting face of the picker carried thereby, so that the stick is not deflected out of its course against or toward either side of the slot by the check. 40 By providing separate supports for the jaws, one at each side of the plane of movement of the stick, the check automatically adjusts itself bodily sidewise to the plane of movement of the stick, with practically no side 45 thrust on the stick even though the path of travel of the latter may vary or change during different picks of the loom as is usually the case.

Other features of my invention are here- 50 inafter pointed out.

Figure 1 is an elevation of a portion of the lay of a loom equipped with a picker-stick check constructed in accordance with my invention.

Fig. 2 is a section on line 2—2, of Fig. 1 55 showing the condition of the jaws when the picker-stick is not in position between them.

Fig. 3 is a section on line 3—3 of Fig. 1.

Fig. 4 is a view similar to Fig. 3 but showing the picker-stick in position between the 60 jaws.

Fig. 5 shows a modification.

Having reference to the drawings, 1 represents a portion of the lay-beam of a loom, and 2 the picker-stick which swings back 65 and forth as usual in the slot indicated by dotted lines at 3 in Fig. 2. When the shuttle, not shown, is thrown through the shed from right to left, Fig. 1, it finds the picker-stick 2 part-way advanced toward the right, 70 hand end of slot 3 and striking the picker-stick drives it quickly and forcibly toward the outer end of the lay-beam. In order to check this sharp outward swing of the stick it is customary to provide a picker-stick 75 check or buffer upon the under side of the lay near the outer end of the slot 3. The form of my improved check that is shown in Figs. 1, 2, 3 and 4 includes a pair of jaws 4 and 5 arranged opposite each other upon 80 the under side of the lay-beam 1 and at opposite sides of slot 3. These jaws 4 and 5 preferably are made from wood and formed near their inner ends with holes 6 (Fig. 3) through them, within which are 85 driven metal bushings 7. Screws 8 extending loosely through these bushings are driven into the lay-beam 1 and serve to pivotally support the jaws. Between the jaws 4 and 5 and lay-beam 1 is a metal yoke 9 90 against which said jaws are held by the said screws 8, the arms of said yoke being made with holes through them for the screws 8 and for another pair of screws 22. The screws 22 extend only through the yoke 9 95 and serve to firmly hold the latter in position against the under side of lay-beam 1, while the screws 8, which extend through both the jaws and the yoke into the lay-beam, are not driven in tight enough to interfere with free swinging movement of the 100 jaws.

Each jaw 4 and 5 is slotted longitudinally near each side for a portion of its length to provide upon its exterior two resilient 105 blades 10 and 11, the two inner blades 10, 10, of the pair of jaws being held against a jaw-centering lug 12 on yoke 9 by a flexible strap

or band 13. This strap or band has one end fixed in position against the outer side of jaw 4 by means of a fastener 14, from which said band extends around the free ends of 5 both jaws. The opposite end of strap or band 13 is engaged by a hook 15 having a threaded shank 16 extending through a screw-eye 17 (Figs. 3 and 4) driven into jaw 5 from the outer side thereof, said shank 10 16 being provided with a thumb-nut 18 (Fig. 3) by means of which the tension of band 13 may be adjusted.

When the stick is driven outward by the shuttle it passes between the separated 15 pivoted ends of jaws 4 and 5 and strikes against the obliquely disposed inner sides of the latter, pressing said jaws outward on their pivots more or less. This pressure of the stick against the jaws stretches the band 20 13 taut and also flexes the blades 10 and 11 with the result that the outward movement of the stick is stopped and the shock of the blow delivered by the stick is absorbed by the blades and band.

25 The stick first strikes the blades 10 near the base of the latter and relatively near the jaw pivots 8 so that said blades and band 13 offer their greatest effective resistance to the entrance of the stick when the 30 momentum of the shuttle and the latter is greatest, but as the stick under progressively slackening speed forces its way in between the jaws it moves nearer the free ends of the blades 10 and farther away from pivots 35 8, with the result that the gripping action of the check remains fairly constant until the slits of the jaws are closed and band 13 is stretched taut, whereupon the stick and shuttle are definitely stopped. It will be 40 observed that the frictional engagement of band 13 with the ends of jaws 4 and 5 offers a yielding resistance to the spreading of the jaws which supplements the yielding resistance offered the stick by the resilient blades 45 10 and 11.

Fig. 5 shows a modification in which the two pivotally supported stick engaging jaws 4^a and 5^a respectively are made solid, and a flexible elastic connector is provided for 50 the free ends of said jaws consisting of a band 13^a, preferably of leather, having one end thereof secured by fasteners 13^b to jaw 4^a, and a spring 181 having one end thereof engaged with the opposite end of band 13^a 55 and its opposite end engaged with the eye 19 of a screw eye 21, the stem of which extends through a hole in a lug projecting from the jaw 5^a and is provided with an adjusting nut 20.

60 My improved picker-stick check is of very simple and durable construction and will last a great length of time even under continuous use. Also it is light and does not add materially to the weight of the lay. It 65 has the further advantage, also, that its jaws

and band are made from materials that are readily obtainable and easily worked so that repairs or replacements of parts can be quickly and easily made.

What is claimed as the invention is:—

1. A picker-stick check comprising a pair of members respectively having at the front and rear of the slot in which the picker-stick works mountings on which they are adapted to turn, and a connector for the said members carried by and moving with the latter causing them to move in unison in conforming to the line in which the picker-stick is moving, and keeping the clamping pressure of the two members against the interposed picker-stick equal at both sides of said stick. 70

2. A picker-stick check comprising members pivoted at opposite sides of the path of the picker-stick, flexibly connected together by means carried thereby and moving therewith to cause them to move in unison in accommodating themselves to the plane of movement of the picker-stick and to act with equal yielding pressure against the opposite sides of the picker-stick. 80

3. A picker-stick check comprising a pair of jaws adapted to engage opposite sides of the stick, means for supporting the said jaws pivotally at opposite sides of the picker-stick slot so that they are adapted to swing forwardly and rearwardly on their pivotal mountings under the influence of the stick, and means carried by the said jaws and moving therewith connecting them together yieldingly to move in unison in conforming to the line in which the picker-stick is moving, the said construction rendering the action equal against both sides of the stick. 90

4. A picker-stick check comprising a pair of wooden jaws arranged alongside of each other and adapted to engage opposite sides of the stick, each of said jaws being slotted longitudinally for a part of its length to provide it with an integral resilient blade; means on said jaws for holding adjacent ends thereof together so as to cause said jaws to yieldingly stop the stick when it is driven between them, and means for pivotally supporting the opposite ends of said jaws at opposite sides of the picker-stick slot, said jaws being movable laterally together under the influence of the stick. 110

5. A picker-stick check comprising a pair of jaws arranged alongside of each other and adapted to engage opposite sides of the stick; means on said jaws for holding adjacent ends thereof together so as to cause said jaws to yieldingly stop the stick when it is driven between them, said means consisting of a flexible band extending around the ends of both jaws and having its ends each fastened to one of the latter, and means for pivotally supporting the opposite ends 120 125 130

of said jaws at opposite sides of the picker-stick slot so that they can swing laterally together under the influence of the stick.

6. A picker-stick check comprising a pair of jaws arranged alongside of each other and adapted to engage opposite sides of the stick; means on said jaws for holding adjacent ends thereof together so as to cause said jaws to yieldingly stop the stick when it is driven between them, said holding means consisting of a flexible band extending around the ends of both jaws having one end fastened to one jaw and the opposite end adjustably connected with the other jaw, and means for pivotally supporting the opposite ends of said jaws at opposite sides of the picker-stick slot, so that the jaws can swing laterally together under the influence of the stick.

20 7. A picker-stick check comprising a pair of jaws arranged alongside of each other and adapted to engage opposite sides of the stick, said jaws each consisting of a bar

of wood longitudinally slotted for a part of its length to provide an integral resilient 25 stick-engaging blade upon its inner side; means on said jaws for holding adjacent ends thereof together so as to cause said jaws to yieldingly stop the stick when it is driven between them, and means pivotally 30 supporting the opposite ends of said jaws at opposite sides of the picker-stick slot so that they are movable laterally together on their pivots under the influence of the stick, said jaw-holding means consisting of a flexible band fastened at one end to one of said jaws and extending around the ends of both jaws, and an adjustable connection fastening the other end of said band to the other jaw. 35

In testimony whereof I affix my signature in presence of two witnesses.
